CLAIM

I claim the ornamental design for a toilet seat and cover, as shown and described.

DESCRIPTION

FIG. 1 is a perspective view of a first embodiment of a toilet seat and cover, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a cross-sectional view thereof, taken generally along lines 6—6 of FIG. 5;

FIG. 7 is a left-side elevational view thereof, the right-side elevational view being a mirror image thereof;

FIG. 8 is a perspective view of a second embodiment of the design;

FIG. 9 is a top plan view thereof;

FIG. 10 is a bottom plan view thereof; and,

FIG. 11 is a left-side elevational view thereof, the right-side elevational view being a mirror image thereof.

The broken lines showing hinges in FIGS. 1 and 8 are included for the purpose of illustrating the invention in use, and form no part of the claimed design.
